UNITED STATES PATENT OFFICE.

JOHN M. HANSEN, OF PITTSBURG, PENNSYLVANIA.

TRUCK.

SPECIFICATION forming part of Letters Patent No. 727,618, dated May 12, 1903.

Application filed May 9, 1902. Serial No. 106,582. (No model.)

To all whom it may concern:

Be it known that I, JOHN M. HANSEN, a resident of Pittsburgh, in the county of Allegheny and State of Pennsylvania, have invented a new and useful Improvement in Trucks; and I do hereby declare the following to be a full, clear, and exact description thereof.

My invention relates to trucks for railway-cars, and more especially to trucks of the diamond-frame type.

The object of my invention is to improve trucks of this character in details of construction, which are hereinafter fully described and claimed.

In the accompanying drawings, Figure 1 is a plan view of my improved truck. Fig. 2 is a side elevation thereof. Fig. 3 is a transverse vertical section of the same. Fig. 4 is a transverse vertical section of one side frame on the line 4 4, Fig. 2; and Fig. 5 is a horizontal section on the line 5 5, Fig. 2.

My truck-frame comprises top and bottom arch-bars, tie-bars, columns, journal-boxes, and the like. The top arch-bar 1 is of inverted-trough shape, having laterally-projecting flanges 2 of suitable width on its lower side. This arch-bar may either have its ends open or else have them closed or boxed in, as shown in Fig. 2. The lower arch-bar 3 preferably is of rectangular cross-section and in general may be of the shape usually employed for members of this kind. The arch-bars are united by rivets 4 at their outer ends and diverge from each other toward their centers.

The tie-bars 4 may be of any preferred form, preferably of rectangular cross-section, and are united to the lower arch-bars near their centers, while their ends are separated from the lower arch-bars to receive the journal-boxes 6 therebetween. These journal-boxes may be of any suitable or preferred construction. They are separated from the arch-bars by means of the liners 7, which lie between the tops of the journal-boxes and the under

side of the lower arch-bar. Liners of various thicknesses may be provided, and they may be changed to suit various conditions. The journal-boxes act as struts between the arch-bars and tie-bars near their ends; and all of these parts are united by journal-box bolts 8 passing through the several members and provided with nuts on their lower ends.

Between the top and bottom arch-bars, near their middle portions, are the columns 10, which are formed of pressed steel plates, having their vertical portions trough-shaped, as shown, and provided with laterally-projecting flanges 11 on their sides. The upper ends of these columns are suitably flanged, as shown at 12, for riveting to the flanges of the top arch-bars. The lower ends of the columns are bent to form the flange 13, through which they are secured to the lower arch-bar. Column-liners 14, formed of bent or pressed metal plates, are riveted to the inner faces of the columns and have their bent ends lying, respectively, underneath the top arch-bar and above the lower arch-bar. These liners are formed of quite wide plates and project inwardly a considerable distance inside of the truck side frames to form supports for the brake-beam end hanger-brackets 15, which are riveted thereto. The spring-plank 16 is of channel shape and extends transversely from side frame to side frame, being riveted to the side frames and lying above the in-turned ends of the columns and liner-plates. This spring-plank supports the usual springs 17, upon which rests the truck-bolster 18. This bolster may be of any preferred or desired construction and is provided with the chafing-castings 19, which bear against wearing-plates 20, formed of rectangular pieces of plate metal attached to the inner faces of the column-liners. Riveted to the lower flanges of the top arch-bar and lying between the in-turned upper ends of the column-liners is a plate 21, which projects inwardly, as shown, and has its inner end flanged to present a bearing-surface of proper size to distribute the side thrust, said plate being adapted to come in contact with the truck side bearing 22, attached to the bolster, and limit the side-wise movement of the bolster.

The truck will of course be provided with the usual brake mechanism; but this forms no part of the present invention, and therefore will not be described. The particular form of brake mechanism shown in the drawings is intended to be illustrative merely.

The truck side frame described is very simple and strong. All of the parts are so formed that the rivets pass through outwardly-projecting flanges or the like, so that hand-rivet-

ing is avoided, thus making it easy and expeditious to assemble the same.

What I claim is—

1. In a car-truck, the combination of side frames composed of top and bottom arch-bars, two separate column-posts having their ends flanged and riveted to said top and bottom arch-bars, said column-posts having their vertical portions trough-shaped, a spring-
10 plank overlapping the lower flanges of the column-posts and secured to the bottom arch-bars and uniting the side frames, and a bolster having its ends projecting between the columns and underneath the top arch-bars.
- 15 2. In a car-truck side frame, the combination with top and bottom arch-bars, of two separate column-posts provided with flanges at their upper and lower ends for riveting to the top and bottom arch-bars, said column-
20 posts having their vertical portions trough-shaped and provided with laterally-projecting flanges, and column-liners applied to the inside faces of said column-posts and secured to the flanges thereof, said column-liners hav-
25 ing their top and bottom ends bent inwardly and lying respectively below the top arch-bar and above the lower arch-bar.
3. In a car-truck side frame, the combination with a top arch-bar of inverted-trough
30 shape and provided with laterally-projecting flanges, of a bottom arch-bar riveted to said

top arch-bar near its ends and diverging therefrom at its middle, and column-posts interposed between said top and bottom arch-bars and having their ends flanged and riveted thereto, said column-posts having their vertical portions trough-shaped and provided with laterally-projecting flanges. 35

4. In a car-truck side frame, the combination with top and bottom arch-bars united near their extremities and diverging at their centers, of column-posts interposed between the diverging portions of said arch-bars, column-liners applied to the inner faces of the columns and projecting inwardly beyond the 40 truck-frame, and brake-beam hanger-brackets riveted to said column-liners. 45

5. In a car-truck, the combination with a bolster provided with a shoulder, of a truck side frame comprising top and bottom arch-bars, column-posts interposed between said arch-bars, and a stop-plate secured to the top arch-bar between the column-posts and projecting inwardly and having its inner end lying in proximity to the shoulder on the bolster. 50 55

In testimony whereof I, the said JOHN M. HANSEN, have hereunto set my hand.

JOHN M. HANSEN.

Witnesses:

A. B. FRASER,
WM. BIRRMAN.
